UNITED STATES PATENT OFFICE.

HARVEY HUBBELL, OF BRIDGEPORT, CONNECTICUT.

ELECTRIC-SWITCH MECHANISM.

1,352,604.

Specification of Letters Patent. Patented Sept. 14, 1920.

Application filed June 17, 1919. Serial No. 304,879.

To all whom it may concern:

Be it known that I, HARVEY HUBBELL, a citizen of the United States, residing at Bridgeport, county of Fairfield, State of Connecticut, have invented an Improvement in Electric-Switch Mechanisms, of which the following is a specification.

This invention has for its object to provide a switch mechanism especially characterized by the fact that the intermittent rotary movements of the contact member are completed with a quick jump or "snap," that is with a great acceleration of speed.

With this end in view I have devised a mechanism of this character in which the rotary movement of the contact member is first retarded and is then subjected to the action of an accelerating spring, and I have illustrated a form of the invention in which the primary actuator is attached to a shaft and is operated thereby, as in snap switches, and another form in which the primary actuator is operated by a lever and oscillates on a fixed shaft, as in ceiling switches.

25 In the accompanying drawing forming a part of this specification,

Figure 1 is a plan view illustrating the first mentioned form of the invention as applied to electric switch mechanism of the snap switch type, the shaft being in section on the line 1—1 in Fig. 2, looking in the direction of the arrows;

Fig. 2 a side elevation of this form of the mechanism complete;

35 Fig. 3 a fragmentary view partly in elevation and partly in section;

Fig. 4 a perspective view of the primary actuator of this form of the invention;

40 Figs. 5, 6 and 7 perspective views respectively of the secondary actuator, the contact member and the accelerating spring, these members being common to both forms of the invention;

Fig. 8 a perspective view of the primary actuator of the second mentioned form of the invention as applied to electric switch mechanism of the ceiling switch type, and

Fig. 9 is a perspective view complete, and Fig. 10 a plan view complete of the second 50 mentioned form of the invention.

55 20 denotes an insulating base which is provided with arc shaped inclines 21, which coöperate in pairs, each incline terminating in an abrupt shoulder 22. Alternate inclines carry contact plates 23 and 24, each of which carries a binding screw 25, and

one of which is provided with a resilient retarding plate 53. 26 denotes the contact member as a whole, 27 the secondary actuator as a whole and 28 the accelerating 60 spring. The primary actuator is retained in close engagement with the secondary actuator by means of a spring 54.

In the snap switch type of the invention, as illustrated in Figs. 1, 2 and 3, 29 denotes the shaft which is provided with a head, shown only by dotted lines, which is seated in a recess in the under side of the base, the shaft being provided with a finger piece or key, not shown, and rotating freely in the 70 base. 30 denotes the primary actuator which in this form is provided with a hole 31 through which the shaft passes, the actuator being locked to the shaft by means of wings 32 which are pinched out from the 75 shaft and engage slots 33 extending radially from the hole in the actuator.

The contact member comprises a plate 34 having a hole 35, a notch 36 in its edge, and downwardly extending contacts 37 which 80 engage contact plates 23 and 24 and the intermediate inclines on the insulating base.

The secondary actuator comprises a plate 38 which rests on plate 34 of the contact member, and a sleeve 39 which passes loosely 85 through hole 35 in the contact member, and is free to rotate independently of said member. Plate 38 of the secondary actuator is provided with notches 40 which are adapted to be engaged by downwardly turned lugs 90. 41 struck out from the primary actuator and with a downwardly turned lug 42 which loosely engages notch 36 in the contact member, so that the parts may have independent movement. The sleeve is provided with an outwardly extending lug 43 which is engaged by a hook 44 on the accelerating spring. The other end of the accelerating spring is provided with a hook 45 which engages one of the contacts 37 on 100 the contact member 26, the left contact as shown in Figs. 3, 6 and 9. In this form, spring 54 bears against a collar 55 on the shaft and against the primary actuator and rotates with said parts.

105 In the ceiling switch type of the invention, as illustrated in Figs. 8, 9 and 10, the shaft, indicated by 47, is anchored in the insulating base and the primary actuator, indicated by 46, is adapted to oscillate 110 thereon and is provided with an operating lever 52. In this form the primary actuator

ator is provided with the lugs 41 to engage the secondary actuator, as before, and with a lug 48 which is engaged by a hook 56 on spring 54. The other end of spring 54 is hooked into a hole in a head 57 on shaft 47. As the shaft is stationary in this form it follows that the spring, in addition to keeping the primary actuator in engagement with the secondary actuator, will be partly wound at each actuation and will act to return the primary actuator to its normal position after each actuation. At the outer end of the lever is a segment 49 to which an operating chain 50 is attached. 51 denotes the usual guide through which the chain passes.

In use, operation of the primary actuator causes lugs 41 to engage notches 40 in the secondary actuator and carry it forward with a step by step movement. If the primary actuator is moved backward, in either form, lugs 41 pass out from notches 40 and backward over plate 38 and then drop into the other pair of notches 40, it being immaterial as already stated, whether the primary actuator is operated by a rotating shaft, or is oscillated on a fixed shaft. The secondary actuator carries the contact member through engagement of lug 42 with notch 36, but as the connection is a loose one the parts have movement independently of each other. The movement of the contact member is necessarily retarded, more or less, through the action of spring 54, which in addition to holding the primary actuator in close contact with the secondary actuator holds plate 38 of the secondary actuator in close contact with plate 34 of the contact member. I preferably, however, additionally retard the movement of the contact member while passing over the contact plates, *i.e.* during alternate actuations by means of the resilient retarding plate 53, which is formed integral with contact plate 23. A retarding plate may be used in connection with each contact plate if preferred, but ordinarily one retarding plate is found quite sufficient. The retarding plate normally lies in engagement with the contact plate, the contact being forced between the contact plate and the retarding plate and caused to lift the latter plate against its resilience. Each forward movement of the secondary actuator through the connection of the accelerating spring to the secondary actuator and to the contact plate, causes more or less winding of the accelerating spring. This is relatively unimportant when the contacts are passing over the intermediate inclines but becomes of vital importance when the contacts are passing over the contact plates. The retarding of the contact member by means of the resilient retarding plate or plates, if two are used, causes an effective winding of the accelerat-

ing spring which, when the contacts reach abrupt shoulders 22 and are released by the retarding plate, acts instantly to throw the contacts past the shoulders with a great acceleration of speed, *i.e.* with a snap, the limit of movement being the travel of lug 42 on the secondary actuator in notch 36 in the contact member. When the contacts are in engagement with the contact plates the circuit is closed. When the contacts rest upon the alternate inclines the circuit is open. Each complete movement of the primary actuator either opens or closes the circuit.

Having thus described my invention, I claim:

1. A switch mechanism comprising arc shaped inclines, alternate inclines carrying contact plates, a contact member adapted to engage alternate pairs of inclines, a secondary actuator having a loose connection with the contact member and permitting limited independent movement of said member, an accelerating spring connected to the secondary actuator and to the contact member, and a primary actuator having a step by step connection with the secondary actuator.

2. A switch mechanism comprising arc shaped inclines, alternate inclines carrying contact plates, a contact member adapted to engage alternate pairs of inclines, a secondary actuator having a loose connection with the contact member and permitting limited independent movement of said member, an accelerating spring connected to the secondary actuator and to the contact member, a primary actuator having a step by step connection with the secondary actuator, and means for yieldingly retaining the actuators in operative relation to the contact member.

3. A switch mechanism comprising arc shaped inclines each terminating in an abrupt shoulder, alternate inclines carrying contact plates, a contact member adapted to engage alternate pairs of inclines, a secondary actuator having a loose connection with the contact member, a primary actuator having a step by step connection with the secondary actuator, and means for accelerating the movement of the contact member when it passes off from the inclines.

4. A switch mechanism comprising arc shaped inclines each terminating in an abrupt shoulder, alternate inclines carrying contact plates, a contact member adapted to engage alternate pairs of inclines, means for actuating the contact member with a step by step movement, and means for accelerating the movement of the contact member as it is passing off from the inclines.

5. A switch mechanism comprising arc shaped inclines, each terminating in an

- abrupt shoulder, alternate inclines carrying contact plates, one of said contact plates being provided with a resilient retarding plate, a contact member adapted to engage alternate pairs of inclines and the retarding plate, and means for accelerating the movement of the contact member when it passes off from the inclines and out of engagement with the retarding plate.
- 10 6. A switch mechanism comprising arc shaped inclines, alternate inclines carrying contact plates, a contact member adapted to engage alternate pairs of inclines and having a central hole, a secondary actuator comprising a sleeve lying loosely in said hole, said secondary actuator having a loose connection with the contact member, an accelerating spring connected to said sleeve and to the contact member, and means for actuating the secondary actuator with a step by step movement.
- 15 7. A switch mechanism comprising a contact member having a central hole and a peripheral notch, a secondary actuator engaging the contact member and having a sleeve loosely fitting in said hole and a lug adapted to loosely engage the notch in the contact member, so that said parts may have independent movement, and an accelerating

spring having its ends connected respectively to the contact member and to the secondary actuator.

8. A switch mechanism comprising a contact member having a central hole and peripheral notch, a secondary actuator comprising a plate resting on the contact member and provided with a downwardly extending lug loosely engaging the notch in the contact member, and a sleeve loosely fitting in said hole, and an accelerating spring having its ends connected respectively to the sleeve and to the contact member.

9. A switch mechanism comprising a contact member having a central hole and a peripheral notch, a secondary actuator comprising a plate resting on the contact member and provided with notches and a downwardly extending lug loosely engaging the notch in the contact member, and a sleeve loosely fitting in said hole, an accelerating spring having its ends connected respectively to the sleeve and to the contact member, and a primary actuator having lugs adapted to engage the notches in the secondary actuator and carry it forward with a step by step movement.

In testimony whereof I affix my signature.
HARVEY HUBBELL.
